FOLDING CASE

Benjamin B. Freifeld, New York, N. Y.

Application May 12, 1942, Serial No. 442,652

6 Claims. (Cl. 129—1)

This invention relates to improvements in folding cases for the carrying and preservation of personal papers, such as the newly issued Government paper ration certificates.

The primary object of the invention is to provide a folding case into which personal papers such as food rationing paper certificates containing tear-away stamps or coupons may be kept to prevent soiling and wrinkling during handling over the period of time for which they are issued.

Another feature of the invention resides in a folding case in which the identifying indicia of the certificates and the tear-away stamps are exposed when the case is open to enable the tearing away of the stamps without removing the certificates from the case.

Another feature of the invention is to provide what may be termed a loose leaf binder in the form of a wallet or folding case in which loose paper sheets may be securely bound therein without the aid of extraneous fastening elements.

A further feature of the invention is the provision of a folding case in which the papers are easily insertable and removable, and which is simple and inexpensive of construction.

Other features of the invention will become apparent as the following specification is read in conjunction with the accompanying drawing, in which:

Figure 1 is an inside plan view of the folding case in open position and with the securing flaps extended, a portion of the case being broken away in section.

Figure 2 is a view similar to Figure 1, but showing three paper certificates in fastened position therein, the lower right corners of the certificates being broken away.

Figure 3 is an enlarged transverse sectional view on the line 3—3 of Figure 2.

Figure 4 is a perspective view of the case in closed position.

Figure 5 is a plan view of a modified form of case formed from a single blank of material, a portion being broken away in section.

Referring to the drawing by reference characters and at present to the preferred embodiment of the invention illustrated in Figures 1 to 4 of the drawing, the numeral 10 designates a folding case or loose-leaf binder in its entirety. The case 10 includes a pair of stiff rectangular shaped cover members 11—11 hingedly connected in book fashion as at 12 by flexible binding material 13. The cover members 11—11 may be made of one or more plies of cardboard 14 suitably covered by 55

imitation leather or like outer binding material 13. Secured to the inside of each cover member 11 is a binding or holding unit 15, the same being made in rights and lefts for attachment to the respective hingedly connected cover members. Each binding or holding unit 15 is constructed from a single blank of material such as leather, cardboard, or cardboard having a fabric backing. Whereas the material from which each unit 15 is constructed is relatively stiff, it is capable of being flexed and folded in a manner and for reasons hereinafter explained. Each holding unit comprises a rectangular attaching panel 16 of a size slightly less than that of the cover, and which panel is centered relative to the cover so as to lie within the confines of the same. An adhesive 17 secures the panel 16 to the inner side of the cover as shown in Figure 3. Formed integral with the top edge of the panel 16 is a substantially L-shaped inwardly extending flange 18, the long portion 19 thereof extending entirely across the panel 16 while the shorter vertical portion 20 terminates some distance short of the bottom edge thereof. Formed integral with the vertical short portion 20 and folded inwardly therebeneath is a glue flap 21 which is adhesively secured to the portion of the panel 16 which it overlaps. The L-shaped flanges 18 cooperate with the panel 16 to provide right angle corner pockets P. When the cover members 11—11 are open as illustrated in Figures 1 and 2, the angle corner pockets P are in reverse relation and slidably receive and hold the top folded edges of the sheets or certificates to be held by the case. Formed integral with the lower edge of the panel 16 is a free tongue flap 22, the side edges of which converge as at 23. The flap 22 is of a length slightly less than the width of the panel 16 so as to lie beneath the L-shaped flange 18 when the tongue flap is folded inwardly on the score or crease 24. In the drawing I have illustrated a folding case 10 for holding and preserving one or more Government ration certificates C, three of which have been illustrated. Each certificate is rectangular in plan having its lower edge provided with a double longitudinal row of stamps or coupons S to be torn therefrom in exchange for the purchase of rationed commodities. If more than one certificate C is to be carried in the case, the same are placed flat in unfolded position, one upon the other in aligned relation. The certificates are folded lengthwise on their mid-portion M and inserted with the folded edge first, in-

wardly of the open cover member until the top folded edge M and upper portions of the free outer side edges enter the pockets P and lie beneath the L-shaped flaps 18. The operator now 5 folds the tongue flaps 22-22 upon the creases 24-24 and by a slight flexing of the tongue flaps, the same are inserted inwardly between the folds of the innermost folded sheet or certificate C as best seen by reference to Figure 3. The inner ends of the tongue flaps 22 and a portion 10 of the outer edges thereof lap the plane of the portions 19 and 20 respectively of the pocket forming flaps 18, thus preventing the accidental slipping out of the tongue flaps which with the flanges 18 prevent accidental removal of the 15 folded certificate. The free edges of the certificate C containing the tear-away stamps S are face up when the case 10 is open, whereupon the same are readily accessible for removal without disturbing the remainder of the certificates. The 20 certificates also contain identification indicia above the rows of stamps which is exposed to view when the case 10 is open. When the case 10 is closed as shown in Figure 4, the certificates further fold on the transverse creases T and the 25 flanges 19-19 and cover members 11-11 are in confronting relation. Thus it will be seen that the certificates C or other loose sheets may be held in a bound condition between the two cover members 11-11 and kept in a neat and clean 30 condition. To remove the certificates C or sheets, it is only necessary to withdrawn the tongue flaps 22-22 from between the folds of the innermost certificate or sheet, and then slide the certificates or sheets from beneath the flanges 18-18.

In Figure 5 of the drawing, I have illustrated a modified form of the invention in which the folding case or binder is constructed from a single blank of leather, imitation leather, card-board or other like material. The blank of material is cut, creased, and folded to provide hingedly connected complementary cover sections 11'-11' having integral inwardly folded substantially L-shaped flaps 18'-18', the short side 40 portions 20' thereof having integral inwardly folded attaching flaps 21' which may be glued or stitched to the cover sections 11'-11'. Connected to the cover sections 11'-11' along the creases 24'-24' are tongue flaps 22'-22'. In 50 use, the folded sheets are inserted beneath the flaps 18'-18' in the same manner as hereinbefore explained and the tongue flaps 22'-22' folded inwardly beneath the folds of the innermost sheet.

While I have shown and described what I consider to be the most practical embodiments of my invention, I wish it to be understood that such changes in materials, design, and construction as come within the scope of the appended claims 60 may be resorted to if desired.

Having thus described the invention, what I claim as new and desire to secure by Letters Patent, is:

1. A case for receiving folded sheets to be bound therein comprising a pair of hingedly connected complementary cover sections, means on the inside of the cover sections for receiving and holding the top folded corner edges of folded sheets, and means normally extending from the lower edges of the cover sections and foldable inwardly thereover and between the folds of the innermost folded sheet and cooperating with said

first means to prevent accidental separation of the sheets from the cover sections.

2. A case for receiving folded sheets to be bound therein comprising hingedly connected complementary cover members, top corner flanges provided on the inside of the cover members at the top outer corners thereof and cooperating with the cover members to form top corner pockets, and tongue flaps hinged to the bottom portions of the cover members and being inwardly foldable thereover, whereby folded sheets may be inserted with their folded edges in said corner pockets and the tongue flaps folded inwardly to lie beneath the folds of the innermost sheet to prevent accidental separation of the sheets from the case.

3. A case for receiving folded sheets to be bound therein comprising hingedly connected complementary cover members, substantially L-shaped inwardly extending flanges provided on the inner side of the cover members at the top outer free corners thereof and cooperating therewith to provide top angular shape corner pockets for slidably receiving the folded edges of folded sheets to be bound, and flexible tongue flaps hingedly connected to the bottom portion of the cover members for infolding thereover and for insertion between the folds of the innermost folded sheet.

4. A case for receiving folded sheets to be bound therein comprising a pair of complementary cover members hingedly connected together in book form, each cover member having a substantially L-shaped flange on the inside thereof with the long portion thereof extending across the top of the cover member and the short portion disposed along the outer side edge thereof and terminating short of the bottom edge, said flange being disposed in spaced relation to that portion of the cover member which it overlaps and cooperating therewith to provide a top corner pocket, and a flexible tongue flap hingedly connected to the lower portion of the inner side of each cover member for infolding thereover, substantially as and for the purpose specified.

5. A case for receiving folded loose sheets to be bound comprising a pair of complementary cover sections hingedly connected together in book form, an angular shaped corner pocket provided on the inner side of each cover member and disposed at the top outer corner thereof, and a flexible tongue flap hinged at the bottom of each cover member and foldable inwardly thereover to cause a portion thereof to lap the plane of the corner pockets when the case is in use.

6. A case for binding folded loose leaf sheets comprising a pair of complementary holder units, means hingedly connecting said holder units together in book form, each of said holder units being constructed from relatively stiff flexible material and comprising a main panel, an angle shaped corner pocket forming flap integral with the top edge of the main panel and folded inwardly thereover, means securing the corner flap in folded position with the same disposed at the top outer corner of the panel, and a tongue flap integral with and connected to the lower edge of the main panel along a crease for infolding thereover and being of a size to cause the outer free end and outer side edge thereof to underlie said pocket forming flap substantially as and for the purpose specified.

BENJAMIN B. FREIFELD.
